Ray E. Dodge, Miami, Fla., assignor to Dodge,
Incorporated, Chicago, Ill., a corporation of
Illinois

Application December 5, 1950, Serial No. 13,283

Term of patent 14 years

(Cl. D29—23)

To all whom it may concern:

Be it known that I, Ray E. Dodge, a citizen of the United States, residing at Miami, Florida, have invented a new and original Design for a Trophy or Similar Article, of which the following is a specification, reference being had to the accompanying drawings, forming a part thereof, in which—

Figure 1 is a top plan view of my new design for a trophy or similar article;

Figure 2 is a side elevational view thereof;

Figure 3 is an end elevational view thereof.

I claim:

The ornamental design for a trophy or similar article, as shown.

RAY E. DODGE.
